US00D828965S

(12) **United States Design Patent** (10) **Patent No.:** **US D828,965 S**
Wen (45) **Date of Patent:** **** Sep. 18, 2018**

(54) **BARK CONTROL**

(71) Applicant: **Jian Wen**, Shanghai (CN)

(72) Inventor: **Jian Wen**, Shanghai (CN)

(**) Term: **15 Years**

(21) Appl. No.: **29/604,313**

(22) Filed: **May 17, 2017**

(51) LOC (11) Cl. **30-99**

(52) U.S. Cl.

USPC **D30/199; D10/104.1**

(58) **Field of Classification Search**

CLAIM

The ornamental design for a bark control, as shown.

DESCRIPTION

FIG. 1 is a front elevational view of a bark control showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

1 Claim, 3 Drawing Sheets
